UNITED STATES PATENT OFFICE.

JOZSEF STOFA, OF ELGIN, ILLINOIS.

TRAIN-PROTECTOR.

1,119,200.

Specification of Letters Patent.

Patented Dec. 1, 1914.

Application filed January 16, 1914. Serial No. 812,601.

To all whom it may concern:

Be it known that I, JOZSEF STOFA, a subject of the King of Hungary, of Elgin, Illinois, have invented certain new and useful 5 Improvements in Train-Protectors, of which the following is a specification.

The object of the present invention is to provide a train with means whereby the entrance of intruders or holdup men may be 10 effectually stopped. This I accomplish by providing drop curtains or barriers at various points of the train as for instance; at the entrance of the engine cab or on the platform of the cars in the train. These I 15 arrange to drop automatically when any-body should step on the platforms of the various cars or engine. When the intruder steps on the platform, a portion of the same is depressed, this completes an electric circuit which operates mechanism to release one 20 or more of the said curtains or barriers. The intruder is then prevented from entering the car or cab, as the case may be. When desired several of these curtains may be employed, so as to inclose the said person and prevent his escape.

I have illustrated the invention in the accompanying drawings, in which;

Figure 1 is a side view of the engine, and 30 car in which is employed my improvement. Fig. 2 is an enlarged side view of a portion of a car to which the said device is attached. Fig. 3 is a horizontal section of the car. Fig. 4 is a rear view of locomotive cab with 35 a portion of the tender in cross section; showing the said device applied to the cab. Fig. 5 is a similar view, showing the drop curtain released. Fig. 6 is a sectional elevation of the box, which holds the folding curtain. Fig. 7 is a sectional detail of a curtain 40 in its released position. Fig. 8 is a section taken on the line $\alpha-\alpha$ of Fig. 6. Fig. 9 is a diagrammatic view, of the car platform; showing the curtain and means for operating 45 the latter, the said curtain being shown in its folded position. Fig. 10 is a diagrammatic view, showing the curtain in its down position. Fig. 11 is a modification of the circuit closer. Fig. 12 is a modification of 50 the curtain and its retaining device.

In the drawings 1 refers to the curtain, which is preferably constructed of a series of articulated strips 2, the same being hinged at 3. The bottom of the curtain consists of 55 a heavy strip or weight 4. The said curtain may be attached by means of screws 5 to the

top piece 6; the whole being inclosed in a box 7.

8-8 are latches, which have projections 9, each of the said latches being pivoted at 10 60 in the box 7, or to a suitable support. Each latch 8 has a cross piece or armature 11.

12 is a magnet, having a core 13, wires 14 and 15 leading from the said magnet to a battery 16, and a circuit closer 17. The said 65 circuit closer has contact points 19 and 20. The circuit closer 17 may be on the platform 21 of a car, or on the engine. When a person steps on the circuit-closer, this will close the circuit, and operate the latches 8-8. The 70 curtain will then drop and form a barrier which will prevent the person from entering the car or cab of the engine, as the case may be.

As shown in Fig. 3 several of the circuit 75 closers may be employed on several points, on the platform; this with the aid of several curtains will prevent the person from entering the car or proceeding from one into the other. It will also, if desired, inclose the 80 person and thus hold him on the platform until taken into custody.

In Fig. 11 I have shown a modification of the circuit closer, which consists of a hinged foot piece 17^a, which may be placed on the 85 engine, so that when a person steps on the same, it will operate the curtain or barrier, and thus prevent the said person from entering the cab.

In Fig. 12 I have shown a modification 90 of the curtain 2^a, the same being rolled up, instead of being folded up, the same being on a roller 30, which has a ratchet 31, and is held by a pawl 32. This is operated by a magnet 12^a, and a circuit closer, similar to 95 the one described in the preceding description.

In Figs. 9 and 10, I have shown means for manually closing the circuit which controls the curtain, comprising a push button 100 42, and a cut-out switch 43. In these figures, two oppositely-disposed gravity dogs 40 are also shown adapted to engage over the weighted bar 4 to secure the lower end of 105 the curtain.

It will thus be seen that my invention provides a very useful device, for the purposes specified.

What I claim is:-

1. The combination with a car platform, 110 of a resiliently-supported treadle device serving as a circuit-closer, electrical con-

tacts below said treadle-device, an electric circuit which includes said contacts, a gravity-drop curtain above said platform, a pivoted catch adapted to engage said curtain and carrying an armature, and an electro-magnet in said circuit adapted to attract said armature.

2. The combination with a car platform having a portion thereof supported upon 10 springs, electrical contact points below said portion of the platform, a box or casing above the platform, a curtain secured at its upper end within said box, a bar attached to the lower end of the curtain, spring 15 catches for engaging said bar and each pro-

vided with an armature, an electric circuit including said contacts, electro-magnets in said circuit in position to attract said armatures, said spring-supported portion of the platform when depressed serving as a circuit closer to close a circuit and energize said magnets. 20

In testimony whereof, I have hereunto subscribed my signature, this 29th day of December A. D. 1913.

JOZSEF STOFA.

In presence of—

JOSEPHINE VERING,
AUGUST SCHOCKE.
